HAIR WAVING CLAMP

Bernard A. Sterling, Chicago, Ill.

Application October 19, 1934, Serial No. 748,992

11 Claims. (Cl. 132—33)

This invention relates to the waving of hair upon the human head, and more particularly to a protector clamp for application to the hair during the waving process.

5 The clamp of my present invention is especially adapted for use in connection with Croquignole waving, but it is to be understood that it may be used elsewhere as suitable and desired.

It is old in the art to apply a protector clamp 10 to a strand or bunch of hair at the scalp and to wind the strand or bunch of hair in overlying layers from its outer end, whereupon a suitable solution and heat are applied to cause the hair to take the desired set.

15 Heretofore, however, the matter of closing and locking the jaws of the clamp upon the hair has presented a rather difficult problem. Particularly, if the strand or bunch of hair is relatively thick it will hold the jaws apart a very appreciable amount, making it necessary with prior 20 devices for the operator to grasp the jaws of the clamp and force them together in order to engage the locking device, if, indeed, it is possible to engage this device at all. The operator is usually a girl, with the result that it is frequently 25 necessary to open the clamp and reduce the amount of hair therein in order to close and lock the same. Even where that is not necessary, the closing and locking of the device has been a difficult matter, requiring at least two distinct operations, which necessitates skill on the part of the operator and reduces the speed of the waving process.

The object of the present invention is to provide simple and conveniently manipulated means 35 for positively and quickly closing the jaws of the clamp and locking the same in closed position.

More specifically, the invention provides, in a hair waving clamp comprising a pair of jaw members pivoted together at one end, a lever pivoted 40 to one of the jaw members at the other end, and a jaw closing and latch member pivoted to the lever and engageable with the other jaw to close the jaws and lock the same in closed position. 45 The jaw closing and latch member has a projecting finger which is adapted to engage the other jaw with the jaws open an appreciable amount, and the pivotal connection between the lever and the jaw closing and latch member is movable into 50 or over dead center position to lock the jaws closed. Further, to facilitate the operation of the device, the other jaw is provided with a roller for engagement with the jaw closing and latch member. The latch member and lever are swingable 55 as a unit about the pivotal connection to

one jaw until the latch member engages the other jaw, and thereafter simultaneously about their respective pivots to close the jaws and lock the same closed. The device is adapted to be closed and locked closed by one continuous manipulation. 5

Another object is the provision of an improved construction of the resilient facing strips for the jaws of the clamp, and particularly an improved formation of the meeting surfaces of these strips 10 whereby to increase the life of these surfaces, particularly along the location at which the bunched strand of hair is gripped.

Another object is to provide a device which will 15 conform better to the head, and in which the disposition of the device with respect to the head will be rendered more uniform throughout the length of the device.

Further objects and advantages will be apparent 20 from the following detailed description, taken in connection with the accompanying drawing, in which:

Figure 1 is a side elevational view, partially in section, on the line 1—1 of Figure 2;

Figure 2 is a top plan view with the jaws in 25 open position, and a bunch of hair positioned between the jaws;

Figures 3 and 4 are fragmentary top plan views 30 showing the action of the device for closing the jaws and locking the same in closed position;

Figure 5 is a cross-sectional view through the jaws of the clamp in closed position, taken on the line 5—5 of Figure 4;

Figure 6 is a view similar to Figure 5, showing 35 a modified form of the heat insulating strips secured to the facing strips of the jaws of the clamp;

Figure 7 is a fragmentary bottom plan view of 40 the modified structure shown in Figure 6; and

Figure 8 is a side elevational view of a modified 45 form of device.

The clamp shown in Figures 1 to 5, inclusive, 50 comprises a pair of elongated arms or jaws 5 and 6 pivotally connected together at one end at 7, and provided at the opposite end with a device 45 for closing the jaws and locking the same in closed position. This device constitutes an important aspect of the invention and will be described fully as this description proceeds.

In the illustrated embodiment, each jaw 5 and 6 55 is in the form of a sheet metal stamping of channel section. It is to be understood, however, that the jaws may, within the scope of the present invention, be of fiber, wood, or any other comparatively stiff material.

At its pivoted end the channel section of the jaw 5 has its top and bottom flanges extended to form projecting tongues 8 which receive, between them, a pair of integral tongues 9 offset to lie 5 closely together and extending out laterally from the top and bottom flanges of the jaws 6. The tongues 8 and 9 are pivotally joined by the pivot 7 which may be in the form of a rivet or of other suitable or preferred form. The pivoted end 10 of the jaw 6 has a tab 11 which is widened and turned up and notched at 12 to receive and support rotatably the adjacent end of the curler, indicated in its entirety at 13.

The back of the jaw 5 terminates short of the 15 free end of the jaw, leaving the projecting tongues 14. The upper tongue 14 is elongated and folded back and turned up at 15 to form one side of the journal for the adjacent end of the curler 13. The back of the jaw 6 likewise terminates 20 short of the free end of the jaw, and the adjacent end of the top flange of the channel section of this jaw is widened, turned up at 16, and notched at 17 to receive and support rotatably the adjacent end of the curler 13, the upturned 25 journal part 15 on the jaw 5 constituting the other part of this journal, and when the jaws 5 and 6 are closed, holding the adjacent end of the curler 13 against lateral displacement from the journal part 16.

30 The inner edge of each jaw 5 and 6 is provided with a facing strip 18 of resilient material, such as rubber or the like. These strips 18 are substantially coextensive with the jaws 5 and 6, and are secured in the channel sections thereof. In 35 the illustrated embodiment, each facing piece 18 comprises a strip of relatively live or yielding rubber, or other equivalent material, grooved at 19 to form a tongue which is pressed or otherwise suitably secured in the channel section of the 40 adjacent jaw and an integral bottom facing piece 21 underlying the bottom flange of the channel section of the jaw. The meeting edges of the facing strips 18 project from the open sides of the channel sections of the jaws to provide yieldable facings for gripping a bunched strand of hair as indicated, for example, at 23 in Figure 2. The meeting edges of these strips 18 may be ribbed or grooved as shown, and a heat insulating strip 25 of wood is preferably glued or 45 otherwise secured to the bottom of the underlying part 21 of each strip 18 to assure adequate insulation between the human head and the heater which is applied to the wound hair in a manner well understood in the art. The strips 25 are 50 substantially coextensive with the jaws, and the meeting edges of these strips are preferably rounded at 26 to diverge in a direction away from the jaws to reduce the length of hair between the scalp and the curler, and to avoid kinking of the 55 hair.

The meeting edges of the facing strips 18 are 60 preferably rounded out slightly at 28 between the ends of the jaws 5 and 6 to give these meeting edges slightly convex form along the location 65 where the bunched strand of hair 23 is gripped. It is found that this materially increases the life of the facing strip along the location where the hair is gripped, and avoids the formation of depressions along these portions of the strip and of 70 such extent as to interfere with the proper gripping action of the jaws.

The particular curler 13 selected for illustration is of the type more fully disclosed in my prior Patent No. 1,862,721, patented June 14, 1932. 75 Suffice it to say that this curler comprises the

metal spool or reel 30 of circular section diminishing in diameter from its opposite ends toward the center and a saddle-like retainer 32 pivoted to one end of the spool at 33. A finger-piece 34 is provided at one end of the spool for turning the same, and the opposite end of the spool has teeth 35 which cooperate with a spring pawl 36 to prevent unwinding of the spool. The spring pawl 36 comprises a spring strip turned in at its upper end for engagement with the teeth 35, 10 and turned in and secured at its lower end at 38 to the top of the jaw 6.

A pad is usually employed in waving the hair as well understood in the art, and for the purpose of receiving and retaining the same I provide a spring retainer 40 secured, for example, by small screws 42 to the back of the jaw 6. The retainer 40 has an upwardly turned integral spring tongue 43, between which and the back of the retainer the substantially flat edge of the 20 pad is received and retained without requiring a thickened edge along the margin of the pad.

The device for closing the jaws and locking the same in closed position comprises a lever 50 pivoted for free swinging movement at one end 25 at 51 between the tongues 14 of the jaw 5. The lever 50 comprises a pair of superposed arched pieces between the pivoted ends of which a washer 52 is provided. A latch 53 is pivoted at 56, preferably relatively stiffly, between the free ends of 30 the arched pieces constituting the lever 50, and this latch 53 preferably has a shoulder 54 which, by engagement with an integral stop 55 turned down from the edge of the top piece of the lever 50, limits swinging movement of the latch in a 35 clockwise direction with respect to the lever 50, as viewed in Figure 2. The pieces constituting the lever 50 have lips 50' turned in to bear against the latch member 53 to prevent free turning of the latch with respect to the lever. As a result, 40 the latch 53 and lever 50 swing substantially as a unit about the pivotal connection at 51 with the jaw 5 and until the latch engages the other jaw, whereupon the latch and lever swing about their 45 respective pivots as will hereinafter appear. The latch 53 has a relatively short projecting finger 57 provided with a rounded cam edge 58 which has a depression 59. The latch 53 also has a finger-piece 60, turned at substantially right angles to the pivoted part of the latch and preferably elongated to give the operator a considerable mechanical advantage in closing and locking the 50 device.

Further, to facilitate ease of operation of the device, the part on the jaw 6 for cooperation with the jaw closing and locking latch 53 is in the form of a roller 62. This roller 62 is mounted between integral tongues 63 projecting endwise from the top and bottom flanges of the channel section of the jaw 6 for free turning movement upon a pin 64 fixed in the tongues 63, as by heading one end and riveting over the opposite end of the pin.

With a bunch of hair between the jaws 5 and 6, as shown at 23 in Figure 2, the device is closed by applying the finger to the finger-piece 60 and 65 pressing the same in the direction indicated by the arrow in Figure 2. This swings the latch 53 and lever 50 as a unit, or at least substantially as a unit, about the pivot 51 until the finger 57 takes over the roller 62 as shown in Figure 3. Thereupon as the finger-piece 60 is pressed further in the same direction, the lever 50 continues its 70 swinging movement in a counter-clockwise direction about the pivot 51 and, at the same time, the latch 53 swings in a counter-clockwise direction 75

about the pivot 56. The resulting action gives the operator great mechanical advantage and forces the jaws 5 and 6 positively to closed position with great force. The roller action, due to the engagement of the roller 62 with the latch 53, further facilitates the closing and locking action, and as the pin 64 moves past dead center $a-a$ (Figure 4), the jaws 5 and 6 are locked positively in closed position.

10 The jaws are released merely by applying the finger to the opposite side of the finger-piece 60 and pressing the same in the direction of the arrow as shown in Figure 4, until the pin 64 moves back over dead center $a-a$, whereupon the 15 bunched hair at 23, or the convex intermediate edges 28 of the resilient facings 18, or both, act to spread the jaws quickly to open position.

From the foregoing it will be apparent that the latch 53 will take over the roller 62 with the 20 jaws 5 and 6 open a considerable amount and with the free end of the lever 59 spaced from the jaw 6. The closing and locking actions are simple and convenient, and are obtained quickly and by one continuous manipulation of the finger-piece 25 60. It is unnecessary first to engage the lever 59 with the jaw 6, and thereafter to manipulate the latch to lock the jaws closed, and relatively thick as well as relatively thin bunches of hair may be handled with equal facility.

30 In the modification of Figures 6 and 7, the heat insulating strips 25' are formed of felt or other equivalent material, and instead of being glued to the facing strips 18', are stitched thereto at the opposite ends, as indicated at 72 (Figure 7).

35 In the modification of Figure 8, the jaws 73, instead of being flat as shown in Figure 1, are of curved or arched form. This conforms these jaws better to the head and, as a result, the disposition of the jaws with respect to the head is 40 rendered more uniform from end to end. In other words, the close proximity of the intermediate portions of the jaws to the head is maintained over substantially the entire length of the jaws. The extremities of the jaws are preferably straightened at 74 and 75 to lie in a common plane $b-b$ for facilitating proper journaling of 45 the curler. And the straightening of the ends 74, where the closing and locking device is disposed, positions this device so that it will swing substantially in the plane $b-b$, or parallel thereto, and not down into engagement with the head, such as 50 might otherwise result if the jaws were arched to their extremities.

I claim:

55 1. In a hair waving clamp, a pair of jaw members, means pivotally connecting said jaw members at one end of the clamp, a lever pivoted to one of said jaw members at the other end of the clamp, and a jaw closing and latch member pivoted to said lever and cooperable with the other jaw member, said lever and jaw closing and latch member being swingable simultaneously about their respective pivots to close the jaw members and to lock same in closed position.

60 2. In a hair waving clamp, a pair of jaw members, means pivotally connecting said jaw members at one end of the clamp, a lever pivoted to one of said jaw members at the other end of the clamp, a jaw closing and latch member pivoted to said lever and cooperable with the other jaw member, said lever and jaw closing and latch member being swingable simultaneously about their respective pivots to close the jaw members, and means for restraining swinging movement of 65 said latch member with respect to said lever until 70

said latch member is brought into cooperation with said other jaw member.

3. In a hair waving clamp, a pair of jaw members, means pivotally connecting said jaw members at one end of the clamp, a lever pivoted to 5 one of said jaw members at the other end of the clamp, a roller on the other jaw member, and a jaw closing and latch member pivoted to said lever and cooperable with said roller to close the jaw members.

10 4. In a hair waving clamp, a pair of jaw members, means pivotally connecting said jaw members at one end of the clamp, a lever pivoted to one of said jaw members at the other end of the clamp, a roller on the other jaw member, and 15 a jaw closing and latch member pivoted to said lever and cooperable with said roller to close the jaw members, the engagement of said latch member with said roller being swingable into or past dead center to lock the jaw members in closed 20 position.

25 5. In a hair waving clamp, a pair of jaw members, means pivotally connecting said jaw members at one end of the clamp, a lever pivoted to one of said jaw members at the other end of the clamp, a latch member pivoted to said lever, and 30 a projecting finger on said latch member for cooperation with the other jaw member ahead of the limit of swinging movement of said lever and operable to close said jaw member and to lock same in closed position.

35 6. In a hair waving clamp, a pair of jaw members, means pivotally connecting said jaw members at one end of the clamp, a lever pivoted to one of said jaw members at the other end of the clamp, a latch member pivoted to said lever, a roller on the other jaw member, and a projecting finger on said latch member for cooperation with 40 said roller ahead of the limit of swinging movement of said lever and operable to close said jaw member and to lock same in closed position.

45 7. In a hair waving clamp, a pair of jaw members, means pivotally connecting said jaw members at one end of the clamp, a lever pivoted to one of said jaw members at the other end of the clamp, a latch member pivoted to said lever and cooperable with the other jaw member to close 50 said jaw members and lock same in closed position, and means for restraining said latch member against free swinging movement about its pivotal connection with said lever whereby said lever and latch member swing as a unit about the pivotal connection of the lever to one jaw member until the latch member is brought into cooperation with the other jaw member and thereafter about their respective pivots to close the jaw members and lock same in closed position.

55 8. In a hair waving clamp, a pair of jaw members, means pivotally connecting said jaw members at one end of the clamp, a lever pivoted to one of said jaw members at the other end of the clamp, a roller on the other jaw member, a latch member pivoted to said lever and cooperable with said roller to close said jaw members and to lock same in closed position, and means 60 for restraining said latch member against free swinging movement about its pivotal connection with said lever, whereby said lever and latch member swing as a unit about the pivotal connection of the lever to one jaw member and until 65 the latch member is brought into cooperation with said roller and thereafter about their respective pivots to close the jaw members and lock same in closed position.

70 9. In a hair waving clamp, a pair of jaw mem- 75

- bers, means pivotally connecting said jaw members at one end of the clamp, a lever pivoted to one of said jaw members at the other end of the clamp, a jaw closing and latch member pivoted to said lever and cooperable with the other jaw member, means for restraining swinging movement of said latch member with respect to said lever until said latch member is brought into cooperation with said other jaw member, and means for limiting swinging movement of said latch member with respect to said lever in the opposite direction.

10. In a hair waving clamp, a pair of jaw members, means pivotally connecting said jaw members at one end of the clamp, and resilient facings for said jaw members, said resilient facings being of generally convex form along the location

where the hair is gripped between said jaw members.

11. In a hair waving clamp, a pair of jaw members arched between their ends for conformity to the head and having straight end portions directed out of the path of curvature of the arched portions of said jaw members, means pivoted to the straight end portion of one of said jaw members on a pivotal axis disposed substantially normal to said straight end portion and swingable out of the path of curvature of the arched portion of said member into and out of cooperation with the straight end portion of the other jaw member for locking said members closed, and means pivotally connecting said jaw members.

BERNARD A. STERLING.
